(57) **CLAIM**

The ornamental design for a hydraulic cutter, as shown and described.

DESCRIPTION

FIG. 1 is a front elevational view of a hydraulic cutter showing my new design;

FIG. 2 is a top plan view thereof;

FIG. 3 is a rear elevational view thereof;

FIG. 4 is a bottom plane thereof;

FIG. 5 is a left side elevational view thereof;

FIG. 6 is a right side elevational view thereof;

FIG. 7 is a left side, top perspective view thereof;

FIG. 8 is a left side, bottom perspective view thereof;

FIG. 9 is a right side, top perspective view thereof;

FIG. 10 is a right side, bottom perspective view thereof;

FIG. 11 is a front elevational view thereof with the cutting blades in a closed position;

FIG. 12 is a top plan view of FIG. 11;

FIG. 13 is a rear elevational view of FIG. 11;

FIG. 14 is a bottom plan view of FIG. 11;

FIG. 15 is a left side elevational view of FIG. 11;

FIG. 16 is a right side elevational view of FIG. 11;

FIG. 17 is a left side, top perspective view of FIG. 11;

FIG. 18 is a left side, bottom perspective view of FIG. 11;

FIG. 19 is a right side, top perspective view of FIG. 11; and,

FIG. 20 is a right side, bottom perspective view of FIG. 11.

The portions shown in broken lines are for the purpose of showing environmental structure only and form no part of the claimed design.

1 Claim, 10 Drawing Sheets
